UNITED STATES PATENT OFFICE.

THOMAS I. DUFFY, OF CHICAGO, ILLINOIS, ASSIGNOR TO LEWIS E. BOWER, OF CHICAGO, ILLINOIS.

DIRIGIBLE SEARCHLIGHT.

Application filed May 15, 1922. Serial No. 560,907.

The purpose of this invention is to provide mechanical connections and controlling means for a universally adjustable device and it is illustrated as applied to a vehicle 5 searchlight or "spotlight" for adjusting the lamp body by connections extending therefrom to a point within convenient reach of the driver. In the particular use shown, the invention involves also the arrangement 10 of electrical connections for the searchlight with a control switch associated with the mechanical control and also details of interior construction for the lamp as well as external supporting means. The invention 15 therefore consists in various features and elements of construction and in their combination as hereinafter described and shown in the drawings and as indicated by the claims.

20 In the drawings:

Figure 1 is a partial elevation of the front wall and wind-shield of an automobile body as viewed from the driver's seat and showing a searchlight embodying this invention 25 supported thereon with control means extending within reach of the driver.

Figure 2 is a vertical sectional view of the lamp body and control connection taken substantially as indicated at line, 2—2, on 30 Figure 1.

Figure 3 is a horizontal detail section taken as indicated at the line, 3—3, on Figure 2.

Figure 4 is a transverse detail section 35 taken as indicated at the line, 4—4, on Figure 2.

Figure 5 is an axial section of the terminal fitting and control handle for the lamp.

Figure 6 is a transverse detail section 40 taken as indicated at line, 6—6, on Figure 5.

Figure 7 is a detail section taken as indicated at the line, 7—7, on Figure 6.

Figure 8 is a fragmental elevation partly in section showing a part of a mounting 45 bracket for the lamp body.

Figure 9 is a detail plan view of a mounting clamp for the control terminal.

Figure 10 is a side elevation, partly in 50 section, showing a modified mounting for the control device.

Figure 11 is a front elevation of a modi-

fied form of bracket and control connection, certain parts being shown in section.

Figure 12 is a vertical sectional view taken as indicated at line 12—12 on Figure 55 11.

Figure 13 is a transverse detail section as indicated at line 13—13 on Figure 11.

The flexible mechanical control embodied in this invention may be applied to various 60 universally adjustable devices, but for purposes of illustration and also for illustrating various specific features, it is shown applied to an adjustably mounted spotlight for an automobile. Heretofore in most 65 cases, such lamps have been provided with universally adjustable mountings by which they were secured to the outside of the vehicle body, but when used on closed bodies of the limousine, sedan or coupé types, they 70

are accessible for adjustment only by opening a door or window which greatly impairs their usefulness, particularly in stormy weather when they are most needed. By the application of my control means, 75 such adjustment is effected from within the car body at any convenient location, as by a control knob or handle secured to the steering column, as shown in Figure 1, or mounted on the instrument board if desired. 80

And because my control connection is a flexible member carried in a flexible tubular casing, the outfit may be manufactured in a standard uniform size and will readily adapt itself to a wide variety of dimensions 85 in car bodies and to various specific locations; furthermore, the flexible connection may enter the body through a relatively small opening in the side wall without impairment to the appearance or strength 90

thereof.

Figure 1 shows a lamp body or shell, 1, swivelly supported for turning about a vertical axis upon a bracket, 2, which is attached to the corner post, 3, of the vehicle body. The arm of the bracket, 2, carries rigidly a swivel post, 4, upon which is sleeved a swivel bearing member, 5, which partially supports the lamp body, 1. Extending downwardly from this mounting 95 Figure 1 shows a flexible tubular casing, 6, passing through a rubber washer, 7, set into 100

the side wall, 8, of the cowl portion of the body, and extending in a free curve to a terminal fitting in the form of a cylinder, 60, from which there projects the control 5 knob, 10. As shown in this view the cylinder, 60, is supported on the steering column, 11, of the vehicle by means of a special clamp device indicated at 12.

Figure 2 shows in detail the mounting 10 and control connections for the lamp body, 1. The outer shell includes a back wall recessed at 13, into which there is tightly fitted a base flange member, 14, which extends rigidly from the rear end of a guide 15 tube, 15, for the lamp socket, 16, in which the base of the incandescent lamp bulb, 17, is removably carried in the usual manner by means of bayonet lock slots in the socket, 16. The forward end of the guide tube, 15, 20 is formed with a terminal flange, 18, notched at 19 for the entry of lugs, 20, on the central flange, 21, of the reflector, 22, which serves to center and steady the forward end of the tube, 15, by reason of the fact that 25 the reflector fits snugly in the forward portion of the lamp body or shell, 1. Said reflector is formed with a peripheral flange, 23, bearing against a yielding gasket which may be in the form of a rubber tube, 24, 30 interposed between the reflector and the edge of the cover glass or lens, 25. Said glass, 25, is cushioned between the gasket, 24, and a similar gasket, 26, pocketed in the in-turned edge, 27, of a bezel ring, 28, which 35 telescopes within the front edge of the shell, 1, and may be locked therein by any suitable means such as studs and slots or grooves of the bayonet lock type, not shown.

The reflector, 22, and cover glass, 25, are 40 yieldingly retained and prevented from rattling by means of spring arms, 29, bearing against the flange, 21, of the reflector and supported upon a bar or plate, 30, of insulated material which is fitted upon the 45 guide tube, 15, primarily to carry the electrical connections for the lamp, 17. These are quite simple, consisting of spring contact arms, 31, held to the insulating bar, 30, by binding screws, 32, which serve also for the 50 attachment of the lead wires, 33. The contact members, 31, enter the guide tube, 15, through clearance slots, 34, and engage the contacts, 35, on the base of the lamp, 17. The socket, 16, is formed of sheet metal bent 55 to provide a cylindrical portion at the forward end encircling the base of the lamp, 17, but extending rearwardly in a U-shaped yoke portion, 36, providing lateral clearance for the contact arms, 31, corresponding to 60 and registering with the openings, 34, in the guide tube, 15. The rear end of the yoke, 36, is threaded to engage a focus adjusting screw, 37, centrally journaled in the rear wall of the shell, 1, for moving the 65 socket, 16, longitudinally to adjust the po-

sition of the lamp filament, 38, with respect to the focal center of the reflector, 22. A coil spring, 39, reacts between the rear wall of the shell and the yoke, 36, to hold the parts in position.

The lower side of the shell, 1, is slotted at 40, to admit a bracket arm, 41, extending from the sleeve portion, 5, which is swiveled on the depending post, 4, of the bracket, 2. A double swinging link member, 42, connects the end of the bracket arm, 41, within the shell, 1, to pivots, 43, set in bosses, 44, which are formed integrally upon the socket guide tube, 15. For the sake of rigidity and smooth action the duplicate links, 42, may be integrally joined by a bridge member, 45, somewhat in the manner of a familiar form of vehicle spring shackle. Extending downwardly within the shell from the guide tube, 15, is a rigid arm, 46, 50 pivotally attached at 47, to the actuator member, 48, of the control means. Said actuator, 48, is slidably and rotatably carried in the bore of the swivel post, 3, and is operatively joined therein to the braided wire cover, 49, which encloses the flexible shaft, 50, of closely coiled wire by which 55 rotative movement is transmitted to the actuator, 48. Said flexible shaft, 50, and its braided wire cover, 49, which makes it longitudinally inextensible though transversely flexible, are carried with some clearance in a flexible tubular casing, 51, which may be of the familiar coiled type as indicated in Figure 2, and said casing is provided with a terminal sleeve, 52, threaded for coupling to the lower end of the swivel post, 4, at 60 53, preferably with a nut, 54, interposed to serve as a step bearing or flange upon which the sleeve portion, 5, of the lamp bracket rests and which may be adjusted in properly spaced relation to the upper flange or shoulder, 55, of the post, 4. When thus adjusted the nut, 54, may be locked in position by the threaded terminal, 52, of the flexible shaft casing.

The actuator, 48, is slotted or bifurcated at its upper end to receive and operatively engage the arm, 46, so that rotation of the member, 48, about its axis will swivel the lamp body, 1, about the same axis, its supporting bracket arm, 41, being co-axially mounted upon the post, 4, by means of the sleeve, 5. Such rotative adjustment of the actuator, 48, may be made by twisting the flexible control member within the casing, 51, through any suitable connections at its remote end. For tilting the lamp body, 1, the actuator, 48, is slidably shifted along its axis within the hollow post, 4, by translation of the flexible shaft within the casing, 6; this moves the horizontal pivot, 47, vertically with respect to the parallel pivot, 56, on which the lamp body is supported through the swinging links, 42, and pivots, 43, on the 100 105 110 115 120 125 130

tube, 15. The links, 42, accommodate the action, permitting the straight line movement of the actuator, 48, to work through the rigid arm, 46, of the tube, 15, but within a limited range, so that the motion of the lamp body is substantially a rocking motion about the pivot axis at 56.

The controlling means for causing these movements of the lamp body may be such as shown in section in Figure 5, comprising a guide cylinder, 60, within which a control member in the form of a rigid hollow rod or tube, 61, is axially mounted to slide through a central opening in one end cap, 62, of the cylinder, 60. At the opposite end, a cap, 63, connects with the coiled casing, 6, of the flexible shaft, 50; said shaft and its braided wire cover, 49, extending within the guide cylinder, 60, for rigid connection with the inner end of the control rod, 61. At the outer end the control rod, 61, is fitted with a knob preferably formed of two parts, a hollow body portion, 64, and a cover, 65, to permit housing an electric switch therein for controlling the current supply to the lamp, 17. One or more radially disposed pins or screws, 66, serve to lock the knob to the hollow rod, 61, so that the rod may be either rotated or slidably adjusted in the cap, 62, of the guide cylinder, 60. Within the cylinder, the part, 61, is further guided by the provision of a hub, 67, with an integral flange, 68, and an applied flange or ring, 69, between which compressible packing material, 70, of annular form is secured for frictional engagement with the inner surface of the guide cylinder, 60. The cap, 62, is screwed on to the end of the cylinder, 60, and pocketed within the cap is a close-fitting washer, 71, of rubber or similar yielding material, and a rigid metal washer, 72, against which the rubber washer, 71, is compressed by adjustment of the cap, 62, so as to frictionally grip the rod, 61, adjacent its bearing in the cap, 62. Thus the friction members, 70 and 71, serve to hold the parts at any position of adjustment, and maintain the spotlight indefinitely in any desired relation to its supporting bracket, 2.

For supplying electric current to the lamp 17, a pair of lead wires which may be enclosed in a common insulating cover, 73, enter the cylinder, 60, through its cap, 63, and are coiled about the control member, 61. Entering the latter through an aperture, 74, the individual wires separate, one of them, being one of the wires, 33, extending through the hollow flexible shaft, 50, to the lamp, and the other wire, 33^a, running in the opposite direction through the hollow control rod, 61, to the switch member in the knob, 64. A disk of insulating material, 75, serves for mounting binding posts, 76 and 77, whose rounded heads diametrically disposed upon said disk, 75, cooperate as contacts with the

rotatable contact disk, 78. As shown in Figure 6, said disk is formed with notches, 79, which avoid contact with the heads of said screws, 76 and 77, at one position; but when the disk is turned 90°, said notches 70 will register with the heads of screws, 80, while the surface of the disk will contact simultaneously with the binding screws, 76 and 77, thus closing the circuit through the wires, 33, leading to the lamp. For simplicity of construction, the screws, 80, may also serve the additional purpose of securing the disk, 75, in the hollow knob, 64. The cover, 65, is screwed on to the hollow body, 64, and locked against rotation by radial screws or pins, 81. A rotatively mounted button, 83, in said cover, is connected to the contact disk, 78, for adjusting it to turn the light on or off. Preferably, as shown in section in Figure 7, the disk, 78, is formed with recesses, 84, to register with the heads of screws, 80, for retaining the disk in the position shown in Figure 6, with the clearance notches, 79, registered around the contacts, 76 and 77. The same recesses, 84, 85 will similarly hold the disk at 90° from this position when the light is turned on. The control device of this type may be mounted as shown in Figure 1, with the guide cylinder, 60, adjacent and parallel to the steering column, 11, and secured thereto by the clamping device, 12, consisting of a bracket having a portion, 91, which partially encompasses the cylinder, 60, with parallel 95 arms, 92, extending therefrom and having flared end portions, 93, adjacent the steering column, 11. A flexible metallic strap, 94, passes around the column, 11, with its end portions extending between the arms, 92, and bearing against the flaring portions, 93. 100 Said ends of the strap, 94, may be provided with a plurality of spaced apertures, 95, to engage with clamping bolts, 96, as indicated in Figures 1 and 9.

Figure 10 shows a modified arrangement 110 in which the guide cylinder, 60, is provided with external threads, 60^a, through a considerable part of its length for receiving threaded mounting flanges, 97 and 98, to be secured against opposite faces of the instrument board, 100. For further securement, screws, 99, may be added, extending through the flanges into the board, 100, as shown. With this arrangement, the flexible casing, 6, will be accommodated entirely back of 120 the instrument board, 100, and out of sight, providing a very neat appearance for the control device.

Figures 11, 12 and 13, illustrate a modification in the mechanical structure of the lamp and its mounting, adapted for operation by the same type of flexible control as that shown in connection with the lamp illustrated in Figure 2. In this instance, the lamp body or shell, 101, is formed with a 130

lateral boss, 102, from which there extends rigidly a horizontal hollow spindle, 103, rotatively carried in a bearing, 104, formed integrally with a vertical bearing sleeve, 105, 5 and at right angles thereto. The sleeve, 105, is mounted between the arms, 106 and 107, of a bracket whose base, 108, is secured to the corner post, 3, of the vehicle body. A hollow cap member 109, screwed into the bracket arm, 106, extends also into the counter-bored end of the sleeve, 105, to serve as a trunnion at 110, and at the lower end of the sleeve, 105, a similar trunnion is provided in the form of a threaded bushing member, 111, screwed up through the bracket arm, 107, with its threaded end depending therefrom for connection with the terminal, 52, of the flexible coiled casing, 6, which encloses the flexible control shaft, 50, and its braided covering, 49. Within the bushing, 111, there is slidably and rotatively mounted an actuator, 112, whose upper portion is longitudinally grooved for engagement with the sleeve, 105, by any suitable key such as 15 the reduced end, 113, of a set screw, 114 (see Figure 13). This permits free longitudinal movement of the actuator, 112, within the sleeve, 105, while insuring that the sleeve will rotate with the actuator when the latter 20 is turned by twisting the flexible control shaft, 50. This provides the rotative adjustment of the lamp body, 101, about the axis of the sleeve, 105. For raising or lowering the beam of light, the spindle, 103, has 25 fixed upon it a gear, 115, and the upper portion of the actuator, 112, is formed with rack teeth, 116, which mesh with said gear and rotate it as the actuator moves up or down in the sleeve, 105. To maintain suitable 30 electric connections throughout this range of movement, the wires, 33, leading through the flexible shaft, 50, emerge from said shaft into a channel, 117, formed in the face of the actuator, 112, beside the rack teeth, 116. 35 Opposite this groove or channel, the spindle, 103, is fitted with a grooved hub or pulley, 118, having a radial aperture, 119, leading into the hollow spindle, 103. Thus the wires, 117, are wrapped once around the 40 grooved hub, 118, and led through its radial opening, 119, into the spindle, 103, which is rigid with the lamp body, 101, containing the electric lamp bulb, not shown. As the actuator, 112, travels up or down rotating the 45 gear, 115, the wires, 33, are reeled on or off the grooved hub, 118, and more or less of their length is accommodated in the channel, 117, of the actuator. To avoid unnecessary slack in the wires, the diameter of the 50 grooved hub, 118, should be such that the reeling and unreeling will take place substantially at the pitch circle of the gear, 115. Figure 8 shows a detail of construction relating to the bracket arm, 2, whereby the 55 lamp may be mounted at either side of the

vehicle body without substitution of any different bracket. The end of the bracket arm, 2, is conically formed at 2^a, and fitted into a conical seat, 2^b, on a base member, 2^c. A clamp screw, 2^d, and washer, 2^e, serve to 70 fix the arm, 2, against rotation in the base when it has been adjusted as desired. As indicated in Figure 1, the base, 2^c, is secured by bolts or screws, 2^f, to the front face of the corner post, 3. To adapt the bracket for 75 attachment to the opposite corner post, 3^a, it is only necessary to loosen the screw, 2^d, and rotate the base, 2^c, 180° on the cone, 2^a, reclamping the bolts in this position,—or if the corner post is not strictly vertical, this 80 construction permits adjustment of the base, 2^c, to any desired angle.

I claim:—

1. The combination of a hollow shell forming a lamp body and means for adjustably supporting the same comprising a bracket having an arm swiveled thereon for rotation about a vertical axis and an actuator rotatably and slidably guided therein for movement about and along said axis, 85 said shell having a slot in its under side through which said swiveled arm extends into the shell, a lamp supporting assembly within the shell and rigid therewith, a link connected by horizontal pivots to said assembly and to the end of the bracket arm within the shell, and a horizontal pivotal connection between said actuator and the lamp body in fixed relation to the latter 90 whereby the movement of said actuator along its axis will adjust the lamp body about its horizontal pivots while rotation of said actuator about its axis will swing the lamp about the swivel axis of the bracket 95 arm. 100

2. In combination with a universally adjustable light projector, a flexible shaft operatively connected thereto and mounted for rotation about its axis and for translation along said axis, together with operating means for imparting either motion to said shaft at will, comprising a rigid tubular terminal attached to the flexible shaft, a cylindrical guide having end walls respectively serving to support slidably the end of said flexible shaft and said tubular terminal, dimensioned to afford an annular clearance space around the terminal within the cylinder, and a guide piston on said tubular member within the cylinder fitted with packing material to frictionally engage the cylinder. 110 115 120

3. In the combination defined in claim 2, said light projector including an electric lamp and a flexible shaft being hollow, a conductor wire extending through said hollow shaft from the lamp and emerging from a lateral opening in the terminal within the cylinder, said wire extending loosely therefrom to an opening in the cylinder wall. 125 130

4. In the combination defined in claim 2, said light projector including an electric lamp and a flexible shaft being hollow, a conductor wire extending through said hollow shaft from the lamp and emerging from a lateral opening in the terminal within the cylinder, said wire being loosely coiled about the terminal tube intermediate said lateral opening therein and an opening in one end 10 wall of the cylinder through which said wire emerges.
5. In the combination defined in claim 2, said light projector including an electric lamp and a flexible shaft being hollow, a conductor wire extending through said hollow shaft from the lamp and emerging from a lateral opening in the terminal within the cylinder, said wire extending loosely therefrom to an opening in the cylinder wall, an 15 operating knob secured to the terminal tube outside the cylinder, an electrical switch device housed in said knob, and conductor 20 wires extending through the terminal tube from the lateral opening within the cylinder to the switch device in the knob. 25
6. In combination with a universally adjustable electric lamp, a hollow flexible shaft operatively connected thereto and mounted for rotation about its axis and for translation along said axis, operating means connected for imparting either motion to said shaft at will, comprising a rigid tubular terminal attached to the hollow flexible shaft, with a hollow knob on said terminal, an electrical switch device housed within said knob with an operating member protruding therefrom, and a conductor wire extending from the light through the hollow shaft and tubular terminal for connection with the switch device in the knob. 30 35 40

In testimony whereof, I have hereunto set my hand at Chicago, Illinois, this 25th day of April, 1922.

THOMAS I. DUFFY.
